UNITED STATES PATENT OFFICE.

HAROLD CAMINEZ, OF DAYTON, OHIO.

OILING SYSTEM FOR CAM ENGINES.

Application filed November 16, 1925. Serial No. 69,437.

This invention relates to internal combustion engines of that type in which the pistons are interconnected by linkage system and are constrained to operate against the cam which is provided on a central shaft. The primary object of the invention is the provision of a novel oiling system for an engine of this character and embraces means for the supply of oil from a reservoir within the central shaft to the connection between the links and the pistons. The oil is supplied to these connections when the pistons are at the inner ends of their strokes and closest to the center shaft.

It is a further object of the invention to provide oil nozzles extending from the central shaft to points close to the ends of the links which interconnect the pistons, in such a manner that the oil is received in a recessed pocket provided at the joint between the links and the pistons.

A further object is the provision of means for periodically causing a supply of oil to be forced through the nozzles by periodically connecting the interior of the shaft with an engine driven oil pump. The oil is thus supplied through the nozzles and also through conduits extending to the periphery of the cam at predetermined points in the cycle of operation.

A further object is the provision of an inner extension on the oil nozzles which communicate with a central part of the reservoir, provided in the shaft in such a manner that the oil is strained through a number of small holes at the inner end of the nozzle. Further objects will be more fully set forth in the following description, the claims and in the drawings, of which—

Fig. 1 is a central section taken through the engine.

Fig. 2 is a section on the line 2—2 of Fig. 1.

Fig. 3 is a section on the line 3—3 of Fig. 1.

Fig. 4 is a section on the line 4—4 of Fig. 5.

Fig. 5 is a detailed view of an equalizing member which interconnects the links and the pistons, and

Fig. 6 is an enlarged central section, taken through the shaft.

Referring more particularly to the drawings by reference numerals, 10 indicates the main casting or housing in which are pro-

vided cylinders 11. The invention is shown as applied to a four-cylinder four-cycle internal combustion engine of the stationary type. The pistons 12 operating in their respective cylinders are provided with ball-bearings 13 suitably mounted upon piston pins 14 which are revolubly mounted in the side walls and in the interior walls 15 of the piston. The rollers 13 bear upon a double lobed cam 16 which is provided with high portions 17 and low portions 18. This cam is fixed upon a main central shaft 19 which is mounted by ball-bearings 20 and 21 at opposite ends of the main housing or casting 10.

Fixed to each piston pin 14 is a pair of short link or stress equalizing members 22 and 23 shown in Figs. 4 and 5. These members are attached to the links 24 by pins 25 in such a manner that the links are free to move about the axis of the pins 25. The interconnection between the pistons by means of these links 24 and the equalizing members 22 and 23, restrains the ball bearings 13 so that they bear upon the cam 16 at all times, and it will be understood that the rotation of the shaft 19 is caused by the pressure exerted upon the cam by the rollers as the charges within the cylinders are exploded in the customary manner. The members 22 and 23 equalize the tension in the links and prevent side pressure of the pistons in the cylinders. The links are provided in sets, one set being located on each side of the cam and all of the links in a set are situated in a plane parallel to the cam.

Fixed upon the shaft 19 is a gear 25 which meshes with a gear 26 on a shaft 27. Shaft 27 drives a gear pump 28 by means of which oil is supplied through a passage 29 to a space 30 provided in the casting 11 as indicated in Fig. 3. A suitable strainer may be provided within this space 30, and a removable plate 31 which closes the lower end of this space 30 provides access for the removal of the strainer. The space 30 at its upper end communicates with a small passage 32 and a series of four round or elongated holes 33 is provided in the shaft 19, so that they will periodically register with the passage 32 as the shaft rotates. A supply of oil will thus be delivered periodically to the reservoir or chamber 34 provided in the interior of the central shaft 19.

Extending from the shaft 19 are four oil

2

nozzles 35, (see Fig. 6). These nozzles are provided with a central passage 36 of a comparatively large size, and a restricted concentrating outlet 37 is provided at the outer end of these nozzles. The inner end of the nozzles extends to a central portion of the chamber 34 so that oil may be supplied to the nozzles from a central portion of the chamber through a series of small openings 38 in the inner end of the nozzle. These nozzles extend outwardly on opposite sides of the cam and on opposite sides of the shaft so that they lie in the same planes as the two sets of links. The nozzles are provided at such points in the shaft so they are close to the low portions 18 of the cam and they are of such length that the outlets 37 are close to the pockets or recesses 39 provided between the two opposite portions 40 and 41 of the equalizing member 22 and the two links to which they are attached. A cut-away portion 42 in the inner sides of the portions 40 and 41 enlarges the opening into this recess or pocket 39 and permits the oil to be supplied to the pins 25. The inner ends of the pockets 39 connect by means of a passage 43 with the inside of the piston pin 14 from which the oil may find its way through a central hole in the piston pin 14, to oil the inner member of the ball-bearing 18. The openings 37 of the nozzles are located so that they will be closest to the pockets 39 in the various equalizing members 22 and 23, when these pockets and the pistons to which members 22 and 23 are connected, are at the inner ends of their strokes and closest to the shaft 19. The holes 33 are so located that the space 30 will be in communication with the chamber 34 within the shaft, at a time when the nozzles are located adjacent to the pockets 39. The pockets 39 will thus be filled with oil periodically and oil supplied to the pins 25.

In order to supply oil to the periphery of the cam, a series of passages 44 are provided through the cam and through the shaft. These passages preferably extend to points between the high and low portions of the cam. The passages 44 are constructed so that the oil flows comparatively slowly through them and the ends of the passages are slightly enlarged as indicated at 45 so that the oil is supplied in a suitable manner to reduce the friction between the ball-bearings 13 and the cam.

The end of the shaft is closed by a plug 46 which is removably attached by means of screw threads so that access may be had within the chamber 34 to clean it.

I am aware that various changes and modifications may be made within the scope of my invention and I do not intend to be limited to the precise form which has been chosen herewith for purposes of illustration.

65 I claim:

1. In a cam engine, a hollow central shaft, a cam thereon having a high portion and a low portion, a number of cylinders arranged radially about said shaft, pistons adapted to reciprocate in said cylinders and having a bearing relation to the cam, a series of links interconnecting the pistons for maintaining the pistons in bearing relation to the cam, means for supplying oil to the interior of said shaft, said shaft having an aperture 70 extending radially in the plane of the series of links and located adjacent a low portion of the cam to supply oil to parts adjacent the ends of the links.

2. In a cam engine, a hollow central shaft, 80 a cam thereon having a high portion and a low portion, a number of cylinders arranged radially about said shaft, pistons adapted to reciprocate in said cylinders and having a bearing relation to the cam, a series of links 85 interconnecting the pistons for maintaining the pistons in bearing relation to the cam, means for periodically supplying oil to the interior of the shaft when one of said pistons is at the inner end of its stroke, said shaft having an aperture in the plane of the series of links and located adjacent a low portion of the cam to supply oil periodically to parts adjacent the ends of the links when the said parts are close to the shaft. 95

3. In a cam engine, a hollow central shaft, a cam thereon having a high portion and a low portion, a number of cylinders arranged radially about said shaft, pistons adapted to reciprocate in said cylinders and having a bearing relation to the cam, a series of links interconnecting the pistons for maintaining the pistons in bearing relation to the cam, means for supplying oil to the interior of said shaft, a nozzle extending from said shaft adjacent the low portion of the cam and communicating with the interior of the shaft for the supply of oil to the points of attachment between the links and the pistons. 100

4. In a cam engine, in combination, a hollow central shaft, a double lobed cam thereon, a plurality of cylinders arranged evenly radially about said cam, a plurality of pistons adapted to reciprocate in said cylinders, a roller for each piston bearing 110 on said cam, a series of links arranged in a plane parallel to the cam and a short distance therefrom to interconnect the pistons to maintain the rollers in bearing relation to the cam, an oil reservoir in the interior of said shaft, a pair of nozzles in the plane of the links communicating with the said reservoir and extending outwardly from said shaft to points close to the points of attachment of the links to opposite pistons with the pistons at the inner ends of their strokes, for the purpose described. 115

5. In a cam engine, in combination, a hollow central shaft, a double lobed cam thereon, a plurality of cylinders arranged 120

evenly radially about said cam, a plurality of pistons adapted to reciprocate in said cylinders, a roller for each piston bearing on said cam, a series of links arranged in a plane parallel to the cam and a short distance therefrom to interconnect the pistons to maintain the rollers in bearing relation to the cam, a second series of links on the opposite side of the cam to interconnect the pistons, an oil passage in the interior of the shaft, an engine operated oil pump for supplying oil under pressure to said passage, a pair of nozzles in the plane of each series of links, the nozzles extending with 15 in said passage and being in communication with central portions of said passage and extending outwardly from said shaft to points close to the points of attachment of the links to opposite pistons when the said pistons are at the inner ends of their strokes.

6. In a cam engine, the combination as set forth in claim 4 together with a pump for supplying oil under pressure to said reservoir, said shaft having a series of holes 25 therein communicating with said reservoir and spaced about said shaft so as to be successively placed in communication with said pump, to cause a periodical discharge of oil from the nozzles when the pistons are 30 closest to the nozzles.

7. In a cam engine, a hollow central shaft, a cam thereon having a high portion and a low portion, a number of cylinders arranged radially about said shaft, pistons 35 adapted to reciprocate in said cylinders and having a bearing relation to the cam, a series of links interconnecting the pistons for maintaining the pistons in bearing relation to the cam, means for supplying oil 40 to the interior of said shaft, a nozzle extending from a central portion of the hollow shaft outwardly to a point adjacent the low portion of the cam for the supply of oil to the parts adjacent the ends of the 45 links when a piston is at the inner end of its stroke, said nozzle having a comparatively large passage therethrough, a comparatively small restricted opening at the exit end thereof and an oil straining forami- 50 nated inlet at the inner end thereof.

8. In a cam engine in combination, a hollow shaft, a cam thereon having a high and a low portion, a number of cylinders arranged about said shaft, pistons adapted to 55 reciprocate in said cylinders, a short link member oscillatably mounted on each piston, a series of links oscillatably attached at their ends to said members to interconnect the pistons and maintain them in bearing 60 relation to the cam, means for supplying oil to the interior of said shaft, and a conduit from the interior of the shaft to a point close to the said members when the said members are closest to the shaft so that 65 the oil may be supplied from the shaft to

the joints between the links and the members.

9. In a cam engine, in combination, a central shaft, a double lobed cam thereon, four cylinders arranged radially about said cam; 70 pistons in said cylinders, anti-friction rollers on the pistons engageable with the cam, a short link member oscillatably mounted on each piston, a series of links all lying in a single plane to one side of said cam, a second 75 series of links in a second plane on the opposite side of the cam, said links being attached at their ends to said members to maintain said rollers in bearing relation to the cam, an oil reservoir, nozzles communicating 80 with said reservoir and located in the planes of the links, said nozzles extending to points adjacent the joint between a member and the links attached thereto when said member is at a predetermined point in the stroke of 85 its piston, so that oil may be supplied to said joint for the purpose described.

10. In a cam engine, in combination, a shaft, a cam thereon having a high and a low portion, a number of cylinders arranged 90 about said shaft, pistons adapted to reciprocate in said cylinders, a short link member oscillatably mounted on each piston, a series of links all in a single plane oscillatably attached at their ends to said members to inter- 95 connect the pistons and maintain them in bearing relation to the cam, said members and a pair of links attached thereto providing a recessed space therebetween, an engine driven oil pump, a series of nozzles in communication with said pump, said nozzles being located at points adjacent the said recessed space when said members are at their innermost position for the supply of a stream 100 of oil thereto.

11. In a cam engine, in combination, a hollow shaft, a double lobed cam thereon, a plurality of opposing pairs of cylinders radially arranged about said cam, pistons adapted to reciprocate in said cylinders, a 110 piston pin for each piston, a member oscillatably mounted in relation to each piston on each piston pin, a series of links oscillatably mounted at their ends to said members to interconnect adjacent pistons together and 115 maintain said pistons in bearing relation to the cam, all the links of said series lying in the same plane to one side of the cam, a second series of links in a second plane on the opposite side of said cam and connected to 120 the said members, each of said members and a pair of links attached thereto providing a recess therebetween which has an opening directed toward the shaft, an engine driven oil pump, an oil reservoir within said shaft 125 supplied by said oil pump, a series of nozzles in each of said planes extending away from the shaft and communicating with said reservoir, the nozzles being situated adjacent the low portions of the cam and extending 130

to points adjacent said recesses when said members are at their innermost positions for the supply of a stream of oil thereto.

12. In a cam engine, in combination, a hollow shaft, a double lobed cam thereon, a plurality of opposing pairs of cylinders radially arranged about said cam, pistons adapted to reciprocate in said cylinders, a piston pin for each piston, a member oscillatably mounted in relation to each piston on each piston pin, a series of links oscillatably mounted at their ends to said members to interconnect adjacent pistons together and maintain said pistons in bearing relation to the cam, all the links of said series lying in the same plane to one side of the cam, a second series of links in a second plane on the opposite side of said cam and connected to the said members, said members and a pair of links attached thereto providing a recess therebetween, an oil passage within said hollow shaft, a series of nozzles in each of said planes extending away from the shaft and communicating at their inner ends with said passage, the nozzles be-

ing situated adjacent the low portions of the cam and extending to points adjacent the said recesses when said members are at their innermost positions, an oil pump, said shaft having a series of radial openings therein communicating with said passage and periodically communicating successively with said pump to supply oil only at predetermined parts in the cycle from said nozzles.

13. In an engine as set forth in claim 11, 35 said members having oil passages therein from said recesses to the piston pins.

14. In a cam engine as set forth in claim 1, and means for supplying oil from the interior of the shaft to the operating face of the 40 cam.

15. In a cam engine, the combination as set forth in claim 4, and a series of passages extending through said cam to supply oil from said reservoir to the periphery of the 45 cam at points between the high and low sides of the cam.

In testimony whereof I have hereunto set my hand this 13th day of November, 1925.

HAROLD CAMINEZ.
